CLAIM

The ornamental design for a swimming aid, as shown and described.

DESCRIPTION

FIG. 1 is a top plan view of a swimming aid;
FIG. 2 is a bottom plan view of the swimming aid of FIG. 1;

FIG. 3 is a left side view of the swimming aid of FIG. 1;
FIG. 4 is a right side view of the swimming aid of FIG. 1;
FIG. 5 is a front view of the swimming aid of FIG. 1; and,
FIG. 6 is a rear view of the swimming aid of FIG. 1.

The broken lines illustrate portions of the swimming aid that form no part of the claimed design.

1 Claim, 4 Drawing Sheets---
